AIR CIRCULATING CASING FOR PLANING MACHINES

James S. Ballantine, Absecon, N. J.

Application August 30, 1949, Serial No. 113,225

8 Claims. (Cl. 144—114)

1

This invention relates to planers and like devices and more particularly to planers equipped with a sealed casing and an air circulating system designed to prevent penetration of dirt, dust, chips, and the like into the driving mechanism.

In the operation of woodworking machines, such as planers, lathes and the like considerable dust and dirt is generated which gradually seeps into the machines collecting on gears, belts, motors and other parts of the driving mechanism. This results in considerable wear and undue heating of the driving mechanism which is particularly aggravated by the use of the usual types of lubricants. Hence it has become the practice to run the gears and other parts of the driving mechanism without lubricants in order to reduce the adverse effects occasioned by dust, dirt and the like.

A primary object of the present invention is the provision of a planer or like device in which the driving mechanism may be lubricated in the usual or any desirable manner without the adverse effects and disadvantages usually encountered by the penetration of dust, dirt and the like.

A further object of the invention is the provision of a planer device in which the penetration of dust, dirt and the like into the driving mechanism thereof is substantially eliminated thereby reducing wear and breakdown with resulting economies of operation and maintenance.

A still further object of the invention is the provision of a planer device in which the driving mechanism including the motors, gears, pulleys, belts and the like for rotating the cutter head and rolls is enclosed and made a part of a continuous closed circuit through which air under pressure is continuously circulated to prevent penetration of dust and dirt from the planing area as well as from the general area surrounding the machine. An auxiliary object is the cooling of the driving mechanism by circulating a stream of air thereover.

Another object of the invention is the provision of a planer or like device in which the gears, belts and pulleys, sprockets and chains, motors and any other desired parts of the mechanism are segregated from the planing area in a closed circulatory path through which air is circulated under a slight positive pressure.

Still another object of the invention is the provision of an air circulating system for planers and the like in which certain parts of the mechanism including the driving mechanism are isolated from the planing area in a closed circu-

2

latory path through which air is circulated under positive pressure to cool the mechanism and to prevent the penetration thereto of dust, dirt and the like.

5 Another object of the invention is the provision of a closed air circulating system for planers wherein the air circulation is produced by a suitable fan, blower or the like driven by one of the motors of the machine and wherein fresh air may enter the system, as needed, through a suitable screened inlet.

These and other objects and advantages of the invention will be apparent to persons skilled in the art from a consideration of the attached 15 drawings and annexed specification illustrating and describing a preferred embodiment of the invention.

In the drawings:

Fig. 1 is a top plan view of a device embodying 20 the invention with the cover removed to show the interior working mechanism;

Fig. 2 is a side elevational view of the device partly in section with the side door open to expose interior working parts;

25 Fig. 3 is a side elevational view of the opposite side of the device with the side door open to expose interior working parts;

Fig. 4 is a broken vertical cross-sectional view of the device taken on the lines 4—4 and 4a—4a 30 of Fig. 2;

Fig. 5 is a perspective view of the cover member; and,

Fig. 6 is a cross-sectional view of the fresh air inlet and filter taken on line 6—6 of Fig. 4.

35 In general the device of the present invention comprises a planer or like device in which the driving mechanism is substantially sealed off from the planing area and the exterior of the machine by enclosing it in suitable chambers or

40 conduits forming parts of a closed circulating system. Air is circulated through the system and around the driving mechanism under a slight positive pressure thereby preventing the penetration of dust and dirt thereto and undue heating 45 of the mechanism.

As illustrated herein the invention is shown as embodied in a planer device having spaced frame or partition members mounted on a base for carrying the cutting, feeding and driving 50 mechanisms and a closed tunnel-shaped member connecting the frame members for housing the motors and electrical controls. The cutting and feeding mechanisms are mounted between the frame members in what is usually called 55 the planing area. The driving mechanism is

mounted outwardly of the frame members which are so constructed as to substantially eliminate penetration of dust and dirt therethrough from the planing area to the driving mechanism. Side doors and a cover are hinged to the frame members and in closed position form therewith and with the tunnel-shaped member the closed circulatory system mentioned above.

Referring now to the drawings the numeral 10 designates a planer having a cutter head 11, 10 pressure and guide rolls 12 and 13, chip breaker 14, and work table 15. The cutter head 11 is rotatably supported by shafts 16 and 17 secured to the ends thereof and mounted in suitable bearings 18 and 19 carried by the side frame or partition members 20 and 21. The rolls 12 and 13 are rotatably supported in a like manner by bearings 22 and 23 carried by the side frame members 20 and 21.

The work table 15 is movably mounted in 20 suitable guides carried by the side frame members 20 and 21 and is vertically adjustable by a handwheel 24 on the front of the casing. Work, such as a board, plank, or the like to be planed, is fed to the device on the work table 15 which is suitably adjusted vertically with respect to the cutter head 11 so that a cut of predetermined thickness will be taken from the work. The work table 15 may and usually is provided with suitable rollers (not shown) to facilitate 30 movement of the work therealong.

The gears, pulleys, and the like for rotating the cutter head 11 and the various rolls of the device are mounted on the ends of their respective shafts outwardly of the side frame members 20 and 21 and are thus separated and isolated from the planing area by said frame members. The motors for driving these various elements, together with the necessary electrical controls and the like, are mounted in a tunnel-like 40 housing 25 which extends transversely of the machine adjacent the rear lower portion thereof. The housing 25 isolates the motors from the planing area but is open at the ends thereof for communication with the space outwardly of the frame members 20 and 21.

As shown more particularly in Figs. 1, 3 and 4 the cutter head 11 is rotated by a pulley 26, mounted on the shaft 27 of a motor 28, and driving the pulley 29, mounted on the end of shaft 16, through a belt drive 30. The various rolls of the device for feeding and guiding the work are rotated through suitable gears disposed outwardly of the frame members 20 and 21 and driven by a pulley and belt connection with a second motor 31. Thus the rolls of the work table are rotated through the gears 32 and 33 (Fig. 2) mounted on the outer ends of the shafts 34 and 35 thereof and driven by the motor 31 through the train of gears indicated generally by the numeral 36. The train of gears 36 is suitably designed and arranged to permit vertical adjusting movement of the work table 15 as required for varying thicknesses of work passed through the device.

The rolls 12 and 13 are also driven by the motor 31 through a gear or sprocket 37 (Fig. 3) mounted on a shaft 38 extending through the machine and having driving connection with the train of gears 36 previously mentioned. The sprocket 37 drives the rolls 12 and 13 through a chain 39 passing over the gears or sprockets 40 and 41 mounted on the ends of the shafts 42 and 43 of the rolls.

From the above description it will be apparent

that the gears, sprockets, pulleys, belts, chains, motors and the like, constituting the driving mechanism of the planer, are separated and isolated from the planing area by the side frame members 20 and 21 and the connecting tunnel-shaped member 25.

The space outwardly of the frame members 20 and 21 is enclosed at the front, rear and bottom of the machine by flanges 45, 46 and 47 which extend outwardly from the frame members adjacent the edges thereof into abutting relationship with similarly arranged inwardly extending flanges 48, 49 and 50 on the side doors 51 and 52. The side doors 51 and 52 are swingably mounted on hinges 53 and 54 secured to the flanges 45 and are adapted to be swung outwardly as shown in Figs. 2 and 3 to permit access to the mechanisms mounted outwardly of the frame members 20 and 21. The doors 51 and 52 are held in closed position by suitable latches 55 and 56.

From the description thus far it will be apparent that when the side doors 51 and 52 are in closed position they form with the flanges 45, 46 and 47 and the side frame members 20 and 21 laterally disposed chambers 57 and 58 which communicate with the tunnel-like housing 25 and with the cover member, as will be described hereinafter, but which are effectively sealed from the planing area and from the exterior of the machine so that dust, dirt and the like may not seep thereinto. If desired, additional sealing off of the chambers 57 and 58 may be obtained by disposing strips of suitable material such as felt or the like between the abutting edges of the flanges 45, 46 and 47 and the flanges 48, 49 and 50.

The chambers 57 and 58 are placed in communication with each other at their top portions through the cover member 60. The cover member 60 is hinged to the rear of the machine and comprises an inverted pan-like member 61 having a top 62, depending front and side walls 63, 64 and 65, and a sloping rear wall 66. Partition members 67 and 68 are connected to the front and rear walls adjacent each side of the cover to form side chambers 69 and 70 which are positioned directly over and in communication with the chambers 57 and 58 when the cover is in closed position. In the arrangement shown the lower edges of the partition members 67 and 68 are adapted to sealingly contact the upper edges of the frame members 20 and 21 and the lower edges of the side and portions of the front and rear walls of the cover are adapted to sealingly contact the upper edges of the flanges 45 and 47 and the top edges of the side doors 51 and 52 to seal the chambers 57, 58, 69 and 70 from the planing area and from the exterior of the casing.

The chambers 69 and 70 are placed in communication through a conduit 71 formed in the cover member 60 and communicating at the ends thereof with openings 72 and 73 formed in the partition members 67 and 68. Thus a closed sealed circulatory system is formed which includes the tunnel-like housing 25, the chambers 57, 58, 69 and 70, and the conduit 71.

In accordance with the present invention air under pressure is circulated through the system by a fan 74 of any suitable type which may desirably be mounted on the shaft 27 of the motor 28 inwardly of the pulley 26. Alternatively the blades of the fan 74 or similar type of blades may be mounted directly on the pulley 26 so as to constitute a fan member which may be satisfactorily used to circulate the air. Rotation of

the fan 74 draws air from the tunnel-like housing 25 and forces it through the chambers 57 and 69, conduit 71, and chambers 70 and 58, back into the housing 25 under a slight positive pressure, for example, about 2 inches of water. As the air circulates through the housing 25 and chambers 57 and 58 it flows over and in contact with the motors, pulleys, gears, and the like constituting the driving mechanism thereby cooling them and since the circulating air is maintained under a small positive pressure the entry of dust, dirt and the like into the system is effectively prevented. This permits the use of any desired type of lubricant thereby increasing efficiency and reducing wear.

Fresh air is admitted to the system through an opening 75 disposed in the rear wall of the housing 25 adjacent the suction side of the fan and serves to replenish any air which leaks out of the system so as to maintain the desired slight positive pressure. An air filter 76 is disposed in the opening 75 to remove dust, dirt and the like from the entering air and may desirably comprise a fibrous filtering element 77 of glass wool or the like coated with a suitable material such as tricresyl phosphate to which the dust will adhere. The filtering element 77 may be retained between foraminous screens or the like 78 and 79 mounted in a frame 80, the latter being held in place in the opening 75 in any suitable manner.

It will thus be seen that the present invention provides a novel and effective means for maintaining the driving mechanism of planers and similar devices free of dust and dirt thereby increasing the effectiveness and useful life of such machines and substantially reducing the possibility of breakdowns.

Various modifications of the invention described and illustrated will most likely occur to those skilled in the art to which the invention relates and may be made without departing from the spirit of the invention, the scope of which is indicated in the attached claims.

I claim:

1. In a planing machine having a horizontal planing table, coating cutting and feeding elements and driving mechanism for said elements, means for substantially sealing said driving mechanism from said cutting and feeding elements so as to prevent penetration of dust and dirt thereto, comprising partition means separating said driving mechanism from said cutting and feeding elements, and hollow casing means associated with said partition means and in combination therewith forming a pressure compartment enclosing said driving mechanism so as to prevent penetration of dust and dirt thereto and means for maintaining said pressure compartment under air pressure.

2. In a planing machine having a horizontal planing table, coating cutting and feeding elements and driving mechanism for said elements, means for preventing the penetration of dust, dirt and the like to the driving mechanism comprising a base member, vertical partition means mounted on said base member and separating the driving mechanism from the cutting and feeding elements, casing means associated with said vertical partition means enclosing said driving mechanism in a closed circulatory pressure system substantially sealed against the penetration of dust and dirt, and means for continuously circulating air under pressure through said circulatory system and over and around said driving mechanism.

3. In a planing machine having a horizontal planing table, coating cutting and feeding elements and driving mechanism for said elements, means for substantially sealing said driving mechanism from said cutting and feeding elements so as to prevent penetration of dust and dirt thereto, comprising vertical partition means separating said driving mechanism from said cutting and feeding elements, a side door hinged to said partition means and enclosing the driving mechanism in a substantially sealed pressure chamber, and means for continuously circulating air under pressure through said pressure chamber over and around said driving mechanism.

4. In a planing machine having a horizontal planing table, coating cutting and feeding elements and driving mechanism for said elements, said driving mechanism including drive gearings located on both sides of the planing table, means for sealing said driving mechanism from said cutting and feeding elements so as to prevent penetration of dust and dirt thereto, comprising vertical partition means on both sides of the planing table separating the respective drive gearings from said cutting and feeding elements, hollow side doors hinged to said partition means and enclosing the drive gearings in sealed chambers, a hollow cover member hinged to said frame members above the planing table and having a passage therein communicating with said chambers, a tunnel-shaped member connecting said partition members below the planing table and communicating with said chambers to form therewith and with the passage in said cover member a closed circulatory pressure system, and air circulating means for continuously circulating air under a slight positive pressure through said circulatory system over and around said drive gearings.

5. A planing machine as set forth in claim 4 in which the air circulating means comprises a fan mounted on the shaft of a driving mechanism motor disposed in the tunnel-shaped member.

6. A planing machine as set forth in claim 5 including a fresh air inlet disposed in said tunnel-shaped member adjacent the suction side of said fan and having a filtering element disposed therein to remove dust and dirt from the entering air.

7. A planing machine as set forth in claim 4 in which the passage between the chambers is housed by a conduit in the cover member located adjacent one end of the machine and the tunnel-shaped member is located adjacent the opposite end of the machine.

8. In a planing machine having planing mechanism including a horizontal planing table and cutting and work manipulating rotary rolls, all said planing mechanism being located in an open planing space, solid vertical partition walls located on opposite sides of said planing mechanism, rotary drive shafts for some of said rolls projecting outwardly through the partition on one side of said planing mechanism through close fitting shaft openings, drive gearings at the outer sides of the respective partitions for the respective roll drive shafts, motor means for driving said gearings, hollow casing members located on opposite sides of the planing mechanism and

75

forming with the respective partitions side pressure chambers housing the respective drive gearings, a hollow top casing member located above the planing mechanism and having an air passage therein communicating with both said side pressure chambers, a hollow lower casing housing said motor means located below the planing mechanism, said lower casing communicating with both said side pressure chambers and forming therewith and with said air passage in the top casing member a closed air recirculating pressure system, and air circulating means adapted to circulate air under pressure through said pressure system in continuous cyclic flow.
